(57) **CLAIM**

The ornamental design for a cervical collar, as shown and described.

DESCRIPTION

FIG. 1 is a front and right side perspective view of a cervical collar showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom and left side perspective view thereof; and,

FIG. 9 is a right side view thereof, shown in condition of use. The broken lines showing a person in FIG. 9 illustrate environmental structure and form no part of the claimed design.

1 Claim, 9 Drawing Sheets(56)
